UNITED STATES PATENT OFFICE.

KARL BAUMANN, OF URMSTON, ENGLAND, ASSIGNOR TO WESTINGHOUSE ELECTRIC & MANUFACTURING COMPANY, A CORPORATION OF PENNSYLVANIA.

STEAM TURBINE.

Application filed March 10, 1922. Serial No. 542,785.

To all whom it may concern:

Be it known that I, KARL BAUMANN, a citizen of the Confederation of Switzerland, and a resident of Urmston, county of Lancaster, England, have invented new and useful Improvements Relating to Steam Turbines, of which the following is a specification.

This invention relates to steam turbines and has for its object to provide improved means whereby difficulties due to the expansion of the casing of a turbine when heated are minimized or avoided.

It is well known in connection with steam turbines, especially those of large size, that a certain freedom of movement must be permitted between the turbine casing and the foundation or sole-plate on which it is supported in order that free expansion of the casing when heated may occur, otherwise distortion of the casing may arise which is liable to cause misalignment of the shaft and rubbing of the rotor or blades against the interior of the casing or other difficulties.

It has been assumed generally that the casing would expand symmetrically on each side of the centre line and consequently any constraints which have been provided have been in the centre line or in a line perpendicular to the centre line. It has been found, however, with very large casings such constraints are not sufficient to guide the casing so that the movement of the axis of the casing has occurred in a direction inclined to the vertical central plane of the machine with consequent rubbing of the rotor on some part of the casing.

In order to avoid this difficulty according to the present invention, guides are provided between the casing and the sole-plate or foundation or other fixed part arranged so as to cause movement of the turbine casing to occur in directions which will cause the casing as a whole to move parallel with the centre line of the shaft. As the casing expands laterally as well as longitudinally, it will be evident that the guides must be placed so as to allow movement of various parts of the casing along lines inclined to the axis, these lines being the directions of the resultants of the laterally and longitudinally acting expansive forces at the points where the guides are located.

In carrying out the invention two additional guides may be provided attached to

the sole-plate or foundation at the inlet end of the turbine and adapted to engage with suitable surfaces formed on the turbine casing or frame at parts equidistant from the central vertical plane and on each side thereof. The guides and the portions of the casing or frame with which they engage are on lines equally inclined to the central axis of the turbine, consequently assuming that the movement of the casing along the lines of the guides is equal, the centre line of the casing will not be displaced from the centre line of the rotor and rubbing between the latter and the casing will not occur.

In order that the invention may be clearly understood it will now be described with reference to the accompanying drawings in which Fig. 1 is a side elevation of a turbine cylinder and pedestal resting on sole-plates and provided with guides in accordance with the invention, a part being sectioned in order to show the securing means at the exhaust end of the cylinder; Fig. 2 is a plan view of the same; Fig. 3 a section on the line III—III, Fig. 1, drawn to an enlarged scale, and Fig. 4 a section on the line IV—IV of Figs. 2 and 3 drawn to the same scale as Fig. 3.

The turbine cylinder 1, at its exhaust end, rests upon the sole plate 4 and is secured thereto by a dowel connection 2 located in the center of the base of the cylinder as shown in Figs. 1 and 2, and by bolts 3. A suitable amount of clearance is allowed between bolts 3 and the sole plate 4 so as to allow for the expansion of the turbine frame in a direction normal to its longitudinal axis. At the steam inlet end the turbine is bolted to two sole-plates 5 and 6 by bolts 7 which are also provided with a suitable amount of clearance to permit expansion of the turbine frame. The bearing pedestal 8 is bolted to a sole-plate 9 and its longitudinal axis is fixed by means of keys 10 which fit into corresponding recesses in the pedestal and sole-plate.

In order to maintain the exact position of the longitudinal axis of the turbine, it is necessary to ensure equal transverse expansion on both sides of the centre line. For this purpose guide keys 11 are provided which fit into grooves 12 and recesses 13 in the base or feet of the turbine and the sole-plates 5 and 6 respectively. The recesses and grooves in the turbine and the

respective sole-plates 5 and 6 are on lines equally inclined to the central axis of the turbine, the angle of inclination marked α in Fig. 2 being determined by the combined 5 longitudinal and transverse expansion of the casing.

The invention is not limited to the construction shown in the drawings and in particular the number and precise location of 10 the guides may be varied, though, as a general rule, it is desirable that the guides should be as few as possible in order that the casing may expand freely when heated.

While I have shown my invention in but 15 one form, it will be obvious to those skilled in the art that it is not so limited but is susceptible of various other changes and modifications, without departing from the spirit thereof and I desire, therefore, that 20 only such limitations shall be placed thereupon as are imposed by the prior art or as are specifically set forth in the appended claims.

What I claim is:

- 25 1. A structure for maintaining correct alignment of a steam turbine when expansion of the casing occurs comprising a sole plate having a dowel connection with one end of the casing in a central vertical plane thereof, guides carried by the sole-plate or foundation at the other end of the turbine and adapted to engage with suitable surfaces formed on the turbine casing or frame equidistant from the central vertical plane 30 on each side thereof and equally inclined thereto, the inclination of each of said surfaces being in the direction of the resultant of the laterally and longitudinally acting expansive forces.
- 35 2. A supporting structure for a turbine casing comprising a sole-plate having a dowel connection in the central vertical

plane of the casing at one end and lateral sole-plates for the other end of the casing having inclined key and groove connections 45 with respect to the casing.

3. A supporting structure for a turbine casing comprising a transverse sole-plate for one end of the casing and having a central dowel connection with respect thereto and sole-plates for the other end of the casing placed equally distant from the vertical central plane of the casing and having groove and key connections with respect to the casing, said key and groove connections being inclined in accordance with the amount of longitudinal and transverse deflection.

4. In a turbine support, the combination 60 of a cylinder fixed at one end against longitudinal movement, supports at the other end of the cylinder on each side of a central vertical plane thereof, and guide means for the supports permitting an angular movement thereof in relation to said plane, said 65 guide means being disposed at an angle to the central vertical plane of the turbine cylinder determined by the combined longitudinal and transverse expansion of the cylinder.

5. In a turbine cylinder supporting structure, the combination of a sole plate, means for fixedly securing the cylinder to the sole plate at one end of the cylinder in a central vertical plane thereof, supports between the 75 sole plate and the cylinder at the other end of the cylinder and guide means for the supports, said guides being disposed in an acute angular relation to the vertical axial plane of the turbine.

In testimony whereof, I have hereunto 80 subscribed my name this fourteenth day of February, 1922.

KARL BAUMANN.
